(57) **CLAIM**

The ornamental design for a magnetic sensor adapter for ultrasonic laparoscope probe, as shown and described.

DESCRIPTION

FIG. 1 is a perspective view of a magnetic sensor adapter for ultrasonic laparoscope probe, showing my new design;

FIG. 2 is a top plan perspective view thereof;

FIG. 3 is a bottom plan perspective view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a rear elevational view thereof;

FIG. 9 is a bottom plan view thereof; and,

FIG. 10 is a cross sectional view thereof, taken along the line 10-10 in FIG. 7.

The broken lines shown in FIG. 10 are for environmental purposes only and form no part of the claimed design.
